Inventor,

Albert H. Smith

By his Attorney

Sheffield & Betts

UNITED STATES PATENT OFFICE.

ALBERT HUGH SMITH, OF MASPETH, NEW YORK, ASSIGNOR TO IMPORT SALES COMPANY, A CORPORATION OF NEW YORK.

ELECTRIC LAMP.

1,181,683.

Specification of Letters Patent.

Patented May 2, 1916.

Application filed August 19, 1915. Serial No. 46,225.

To all whom it may concern:

Be it known that I, ALBERT H. SMITH, a citizen of the United States, and a resident of Maspeth, Queens county, Long Island, 5 State of New York, have invented certain new and useful Improvements in Electric Lamps, of which the following is a specification accompanied by drawings.

This invention relates to electric lamps 10 and particularly to electric lamps adapted for ornamental purposes, such for instance as the illumination of Christmas trees.

The object of my invention is to provide 15 an electric lamp which shall be simple and economical in construction, reliable in operation and attractive in appearance.

In the drawing: Figure 1 is a front elevation of my improved device; Fig. 2 is a longitudinal sectional view thereof; Fig. 3 20 is a fragmentary view similar to Fig. 2 on an enlarged scale, and Fig. 4 is a perspective view showing the clamp removed from the socket.

Referring to the drawing, 10 indicates a 25 hollow cylindrical member preferably of some insulating material, such as cardboard. This member 10 is adapted to receive the electrical conductors 11 which branch off from the main conductors 12 30 which are adapted to be connected to some suitable source of current, not shown.

The conductors 11 are connected in any 35 suitable manner to the lamp socket 13 located at the top of the member 10. This lamp socket, best shown in Fig. 4 is provided at the top with a flange adapted to bear against the end of the member 10, as shown in Fig. 3. Cut from the flange 14 are the projections 15.

40 The clamping member 16 comprises the annular rim 17, and the downwardly projecting prongs 18. In the rim 17 there are formed recesses 19 adapted to receive the projections 15 of the socket 13.

45 In assembling my device, the clamp 16 is placed over the socket 13, so that the projections 15 coöperate with the recesses 19. The projections 15 are then bent over so as to hold the socket and clamp together.

50 These parts are then placed upon the member 10, so that the socket fits into one end thereof, while the prongs 18 extend along

the exterior. Pressure is then applied to these prongs to cause them to penetrate the outer surface and thus positively retain the 55 clamp and socket in position.

The parts having been assembled as above described, they are inclosed and concealed by a sleeve 20 which may be of any desired material. The exterior surface of 60 this sleeve is preferably made to simulate the surface of a candle, so that my device when completed and applied to the object to be illuminated, such as a Christmas tree, is very ornamental as compared with the 65 crude lamp sockets now in general use.

Any suitable lamp 21 may be placed in the socket 13. At the opposite end of the device I provide some suitable means for securing the device in position, the means 70 here illustrated comprising a piece of wire 22, passing through holes in the members 10 and 20. I find that this simple expedient operates very satisfactorily for securing my device to such an object as a branch of a 75 Christmas tree.

While I have here illustrated but a single one of my improved lamps, it is to be understood that as many of them as desired may be connected to a corresponding number of 80 branches 11 from conductors 12. The several branches may be connected in series or multiple, as desired, depending upon the voltage applied to conductors 12, the size of the lamps 21, etc.

85 From the above description, it is apparent that I have provided an electric lamp which is less expensive in construction than the lamps now in common use and which is at the same time more attractive in appearance.

90 I have shown and described a particular embodiment of my improved lamp, but it is obvious that many changes may be made therein by those skilled in the art, without departing from the spirit of my invention.

95 I claim the following:

1. In a device of the character described, a hollow cylindrical member adapted to inclose electrical conductors, a lamp socket located at one end of said member and connected to said conductors, a clamp overlying the lamp socket and provided with prongs adapted to coöperate with said member to retain the socket in position, and a sleeve,

the outer surface of which simulates a candle adapted to surround and conceal the member, socket and clamp.

2. In a device of the character described, 5 a hollow cylindrical member adapted to inclose electrical conductors, a lamp socket located at one end of said member and connected to said conductors, a clamp overlying the lamp socket and provided with prongs 10 adapted to coöperate with said member to retain the socket in position, a sleeve, the outer surface of which simulates a candle adapted to surround and conceal the member, socket and clamp, and means located at 15 the other end of the member and sleeve for retaining the device in position.
3. In a device of the character described, 20 a hollow cylindrical member adapted to inclose electrical conductors, a lamp socket located at one end of said member and connected to said conductors, said socket being provided at the top with a plurality of projections, a clamp for retaining the socket in position; comprising an annular ring provided with recesses for receiving said projections and with prongs adapted to penetrate 25 the surface of said cylindrical mem-
- ber, and a sleeve, the outer surface of which simulates a candle adapted to surround and conceal said member, socket and clamp. 30
4. In a device of the character described, 35 a hollow cylindrical member adapted to inclose electrical conductors, a lamp socket located at one end of said member, and connected to said conductors, said socket being provided at the top with a plurality of projections, a clamp for retaining the socket in 40 position, comprising an annular ring provided with recesses for receiving said projections and with prongs adapted to penetrate the surface of said cylindrical member, a sleeve, the outer surface of which simulates a candle adapted to surround and 45 conceal said member, socket and clamp, and means located at the other end of the member and sleeve for retaining the device in position.

In testimony whereof I have signed this specification in the presence of two subscribing witnesses.

ALBERT HUGH SMITH.

Witnesses:

GEORGE S. DANIELL,
T. J. SMITH.
